Specification of Letters Patent.

Patented Oct. 25, 1921.

Application filed December 1, 1917. Serial No. 204,984.

To all whom it may concern:

Be it known that we, CLINTON R. BARRY and MARSHALL L. McCLELLAND, citizens of the United States, residing at Fort Smith, in the county of Sebastian and State of Arkansas, have invented new and useful Improvements in Drills, of which the following is a specification.

This invention relates to improvements in the art of drilling oil wells, and has for its object to produce a means whereby a well may be effectively drilled at a great saving in time, material and labor, and wherein the well known obstacles incident to the ordinary drilling of said wells will be successfully overcome.

In oil fields, the ground formation strata below the earth's surface, naturally varies in accordance with the geographical location of such fields. In oil fields, however, the cutting elements of the drill are required to bore through both hard and soft strata. Frequent contact of the boring tool with rock, slate, and such hard formations require the frequent resharpening or replacing of the cutting elements of the boring tool, but in boring through soft strata, the cutting elements of the boring tool or drill are not materially affected, and, as a matter of fact, the weight of the boring tool or drill, combined with that of the casing stem, assists the drill in readily boring or plowing through such soft earth formation. Among such soft strata, deep beds of clay, known as "gumbo" and heavy beds of quicksand are encountered. The gumbo is of a soft putty-like consistency and will readily cave into and fill up a hole formed by the drill, should the casing be removed for the resharpening or replacing of the drill. Thus, gumbo, quicksand, or any other very soft formation which is frequently encountered, makes successful and speedy drilling almost impossible and very expensive with the drilling appliances of the ordinary construction. Cable rigs for such drilling cannot be employed successfully, and resort must be had to the rotary drilling system in order to penetrate strata of this character. The use of the rotary drilling system, however, is attended with much difficulty and expense because of the fact that the entire casing must be removed from the hole to replace

or resharpen the drill bit, and, by reason of this fact, the rotary system is not adapted to the drilling or boring of hard rock or strata, as the bit or cutting element must be frequently resharpened or replaced while boring in such hard formations and the time and labor that is consumed in so frequently removing the entire casing from the hole makes the rotary system impractical for hard rock drilling.

Time in well drilling is considered a factor greater in importance than the expense of the material employed in the drilling, but, the latter must also be considered an important item. To remove a rotary drill stem from the hole requires a considerable amount of time and labor and the replacing of the same in the hole requires a still greater amount of time and labor; as a matter of fact, a rotary drill stem cannot be successfully replaced in a hole filled in by gumbo or by quicksand without entirely re-drilling such hole through the bed of gumbo or quicksand, as the case may be.

Unless the hole made by the drill is of a greater diameter than that of the casing, the contact of the strata with the casing materially interferes with the free rotary or vertical movement thereof, and, consequently, it is necessary that the cutting elements of the drill provide for this contingency.

In order that the necessity of withdrawing the casing stem from the hole in order to change or resharpen the parts of the boring tool or drill bit which form the cutting elements may be obviated, and that thereby the time and expense usually spent in this operation may be saved, while at the same time a hole of substantially larger diameter than the casing stem may be drilled by the drill bit, and the drill bit itself may be of such construction that all parts may be subjected, we have devised a detachable rotary drill bit which may be readily withdrawn through the casing stem and which, in its working position, will cut a hole large enough to accommodate the casing stem and is of such construction that all parts are large enough to bear the strain imposed upon them.

All rotary bits heretofore used in drilling deep wells have been rigidly attached to the lower end of the casing, and no means has

heretofore been provided whereby the weight resting upon the bit, or cutting elements, can be controlled with uniformity by the driller. In using the means now employed in rotary drilling, the driller attempts to regulate the weight resting upon the drill bit by raising or lowering the entire casing, which has a weight of many tons, and, as the downward pressure is tended to be applied to the bit by the driller is a great deal less than the weight of the casing, great skill and practice is required to so manipulate the casing that the bit bears on the bottom of the hole with only sufficient force to drill and with not enough pressure that the rotary motion of the bit is arrested. The weight resting upon the bit, should vary with the hardness and toughness of the rock or stratum in which it is boring.

In the ordinary construction of rotary drills employed in drilling deep wells, the hole through the cap-rock over the oil sand cannot be sealed up and a water-tight joint between the cap-rock and the casing made without removing the casing and setting drill stem in the well; the pipe or casing employed as a drill stem cannot be made to serve as a permanent casing for the completed well without first removing it from the hole and removing the bit from the lower end of the stem, after which the casing stem may be replaced in the well and serve as permanent casing. This is expensive and has proved very unsatisfactory, in that much valuable oil is wasted while making the change, and if a very strong gas pressure is encountered in the oil sand, the well may be entirely ruined by the escaping gas destroying the walls of the uncased well.

A still further important feature in well drilling is the provision of means whereby certain sections of strata may be removed for examination or analyzing, the driller, upon such examination or analysis, ascertaining the proximity of his drill to the oil sand, and no provisions have been made for the removal of such strata in any construction of drills with which we are acquainted.

It may, therefore, be considered the primary object of our invention to provide means for overcoming the above mentioned objectionable features encountered in drilling and to simplify and improve the existing art by producing a drilling apparatus of a simpler, cheaper and better arrangement of parts than has hitherto been known in this art, and which will perform their functions in an expeditious and highly satisfactory manner.

With these and other objects in view, which will appear as the nature of the invention is better understood, the same consists in the novel construction, combination and arrangement of parts hereinafter more fully described, illustrated and claimed.

The essential features of the invention involved in carrying out the objects above indicated, are necessarily susceptible of embodiment in various forms of construction without departing from the scope of the invention, but certain preferred and practical embodiments are exemplified by the accompanying drawings, in which,

Figure 1 is a side elevation, parts being broken away and parts being in section, of our improvement.

Figs. 2 and 3 illustrate, upon an enlarged scale, an approximately central vertical longitudinal sectional view of the improvement, the former illustrating the lower part and the latter the upper part of the device.

Fig. 4 is a sectional view upon an enlarged scale approximately upon the line 4—4 of Fig. 1.

Fig. 5 is a transverse sectional view approximately on the line 5—5 of Fig. 2.

Fig. 6 is a similar sectional view approximately on the line 6—6 of Fig. 2.

Fig. 7 is a similar sectional view approximately on the line 7—7 of Fig. 2.

Fig. 8 is a sectional view substantially similar to Fig. 6 but showing the reamers in their retracted position.

Fig. 9 is a transverse sectional view approximately upon the line 9—9 of Fig. 3.

Fig. 10 is a sectional view through a portion of the casing and illustrating the construction of the fishing tool for removing the bit and reamers.

Fig. 11 is a sectional view approximately on the line 11—11 of Fig. 10.

Fig. 12 is a sectional view approximately on the line 12—12 of Fig. 10.

Fig. 13 is a detail plan view illustrating the roller member between the toggle arms of the centering device for the pin designed to be engaged by the fishing tool.

The casing stem 15 is made up, in the usual manner, of a desired number of threadedly connected pipe sections. On the end of the lower section of the stem 15 is threadedly secured a tubular sleeve 16, of any desired length, which constitutes an element of the stem 15, the said sleeve, at its lower end, and upon its inner periphery, being formed with an annular enlargement or flange 17. The flange 17, upon its inner surface, is provided with spaced longitudinal depressions 18 providing ribs 19 between the said depressions.

Arranged in the sleeve 16 is a tubular member, hereinafter known as a follower or shoe, 20 which has its upper or outer edge provided with an annular flange 21 that contacts with the inner surface of the sleeve 16. The follower or shoe 20 has its outer or lower end extending through the sleeve 16 and this end has secured thereon an outwardly extending collar 22. Resting on the upper shoulder provided by the collar 22 is

a compressible gasket 23 designed to receive the outer end of the flange 17 when the casing stem and sleeve are moved downwardly toward the collar 22, or when the follower 5 20 is telescoped in the sleeve. The follower 20, on its outer surface, is provided with longitudinal depressions 24 forming the said outer surface with ribs 25 between the said depressions, the ribs 25 being received in the 10 depressions 18 of the sleeve 16, and the ribs 19 of the sleeve 16, being received in the depressions 24 of the follower 20. By this arrangement, it will be seen that the follower 20 while afforded a limited free longitudinal movement through the sleeve 16 is 15 held against lateral or rotary movement independent of the sleeve.

Arranged in the follower 20, and extending therethrough, is a hollow drill bit made 20 up, in the construction illustrated by the drawings, of three sections, the upper section being indicated by the numeral 26, the intermediate section by the numeral 27, and the lower section by the numeral 28. The 25 intermediate section of the drill bit has its central portion in the nature of a block provided with a substantially rectangular pocket 29, and having openings 30 in the opposite longitudinal walls of the pocket, the 30 said openings entering the pocket from the outer surface of the said section 27. The upper and lower walls provided by the pocket, in a line with the openings 30, but inward of the said openings, are provided with 35 apertures 31 which permit of the free flowing of the water from the casing stem 15 to the lower portion of the drill bit section 28. By reference to Figs. 2, 6 and 8 of the drawings, it will be seen that the collar 22 40 partly closes the transverse openings 30 of the central or intermediate section 27 of the bit, and by reference especially to these Figs. 6 and 8 of the drawings, it will be noted that the depending portion of the collar, in a line 45 with the said openings is formed, upon its inner face with longitudinally extending arcuate depressions 32 that terminate in angular shoulders 33, and the purpose of this arrangement will presently be apparent.

The 50 reamers are indicated by the numerals 34, and, as disclosed by the drawings, comprise each a substantially rectangular body portion 35 of a size and shape to slide in the pocket 29, the said body portions of the 55 reamers being of a length greater than one-half of the length of the said pocket and being of a cross sectional area corresponding to the area of a rectangular opening 30. The cutting surfaces or edges of the reamers are 60 formed upon the lower and outer ends of the body portions 35. The upper edges of the said cutting portions of the reamers being arranged approximately centrally of the body whereby the cutting portions 36 may 65 be projected through the openings 30 out- ward of the pockets 29, (in a manner presently to be described) and have their upper surfaces flush with the lower edge of the collar 22, as clearly shown in Fig. 2 of the drawings. The cutting surfaces 36 are 70 rounded from the upper edges thereof inwardly to the lower edge of the body as shown in the drawings, but instead of being so rounded the cutting edge may be substantially square, or in any other shape found to 75 be efficient, and the outer edges of the said cutting surfaces are beveled as indicated by the numerals 37, whereby the rounded cutting surfaces of each of the reamers is provided with a knife edge.

The body 35 of each of the reamers is provided adjacent its cutting surfaces with a substantially vertical V shaped depression 38 corresponding in shape to and adapted to engage a portion of the walls of the before 80 mentioned depression 32 in the collar 22 when the reamers are brought to an operative position. Engaging the remaining arcuate portion of the arcuate wall of the depression 32 is the arcuate surface 39 of the 85 reamer. The exact construction and engagement between the walls of the depression 32 and the walls of the depression 38 and arcuate surface is an important feature of our construction as the reamers are effectually 90 reinforced against torsional strain and against movement toward an inoperative position and this prevention of inward movement of the reamers is materially aided by other parts to be described later. Each of 95 the upper and lower walls of the pocket 29 has formed therein a pair of rectangular openings 43 and 44 arranged slightly out of alignment with each other but having a restricted communication with each other to 100 form shoulders 41 and 42 at a point axially of the intermediate member 27 for a purpose hereinafter described.

The operative device for the reamers is in 105 the nature of a plate or mandrel 45 and includes a stem 46 rectangular in cross-sectional area and a head 47 having a cross-section equal to that of the stem 46 with the exception that ribs 48—48 are formed upon 110 opposite faces of the head in positions to cooperate with the body of the head to engage the walls of the openings 43 and 44 and guide the mandrel in its movements. By referring to Fig. 5 it will be seen that by striking the ribs from the faces of the head shoulders 49—49 are formed for a purpose hereinafter described. Arranged in the opposite 115 faces of the head and running parallel with the ribs part way of their length, are channels 50—50 which communicate with oppositely disposed angularly arranged grooves or channels 51 and 52 crossing each other at a central point and making their exit at the 120 lower end of the stem for the purpose of allowing the parts to be readily assembled.

The head 47 has its free or upper end formed into an enlargement 54 sliding within the upper member 26 and having formed therein water openings 55. Threaded to the 5 enlargement 54 or connected in any suitable manner is an operating bar 56 for the bit. This bar 56 is centrally provided with a slot 57 and passing through this slot and through oppositely disposed openings in the upper member 26 are pins 58 which limit the upward movement of the mandrel through the 10 bit.

It is of course to be understood that the construction of the bar 56 and pins 58 can 15 be such that the bar may act in the capacity of a "jar" and should this be desired the exit ends of the grooves 51 and 52 may extend a determined distance in a vertical direction before making their exit at the end 20 of the mandrel.

The upper section 26 of the bit, at the outer end thereof, is thickened or otherwise provided with an outwardly arranged annular flange 59, the said flange being provided 25 with spaced longitudinal openings 60 and with continuous or transverse depressions 61. The last mentioned depressions are designed to have arranged therein flexible metallic bands 62 which contact with the outer 30 ends of the pins or rods 58 to retain the same removably connected to the upper section of the bit.

The lower edge of the shoulder 63 provided by the annular enlargement or flange 35 59 rests upon the outer edge of the flange 21 of the follower 20 so that the drill proper is supported on the follower 20 which in turn 40 rests on and engages the reamers when the latter are in operative positions and thus the weight of the follower and drill parts and the boring tool (hereinafter described) carried by the lower section of the drill, will 45 force the reamers as well as the lower boring element or member against the work without necessitating the weight of the heavy line of pipe comprising the casing stem influencing either the reamers or the lower boring tool of the bit in their operation, and, further, so that adding a heavy or light bar of 50 steel, which we will call a "sinker bar" by threadedly connecting it to the threaded pin 90 on the upper end of the mandrel, changeable weight may be added to the bit as in the judgment of the operator is most suitable 55 for boring whatever kind of rock the bit may be working in.

Each of the reamers 34 upon the inner face thereof, is provided with an outwardly extending lug 64, which may take the form of 60 a screw mounted in the reamer and which is preferably round in cross section, and which is designed to be received in the respective channel upon the face or side of the mandrel. When the mandrel is moved in an upward 65 direction, (in a manner which will be pres-

ently described), the lugs 64 will ride freely through the straight branches 50 of the channels in the mandrel, but when the opposite walls provided by the angular branches 51 and 52 of the said channels contact with 70 the lugs, the reamers will be drawn inwardly to their pockets, as illustrated in Fig. 8 of the drawings.

When the mandrel is entirely removed, the exit ends of the directing channels permit of the lugs being readily arranged in the said channels, and when the mandrel is lowered, by the weight thereof, or otherwise, the lugs following the contour of the channels will cause the reamers to be projected to their 80 operative position. The downward movement of the mandrel is limited by contact of the upper end of the slot 57 upon the bar or pin 58, and when the mandrel is in its lowered position, the inner corners of the 85 reamers will be brought to contact with the respective shoulders 49 formed upon the inner faces of the ribs 48 in the head portion 47 of the mandrel, as clearly illustrated in Fig. 6 of the drawings, so that in combination 90 with the interengagement of the walls of the depression 38 and the arcuate surface 39 of the reamers with the shoulders 33 and depressions 32 of the collar 22, the said reamers are retained against inward movement with respect to their pockets, and the contacting engagement of the ribs and shoulders on the head portion of the mandrel with the said reamers reinforce and strengthen the same to withstand the strain 100 subjected to the points thereof, as hereinbefore referred to.

In concluding our description we wish to call attention to the fact that when the drill and its associated parts are moved from the 105 casing, movement of the casing stem into engagement with the follower gasket 23 will cause the collar 22 to act in the capacity of a shoe and for this reason this member should be of hardened material. The gasket 110 23 insures a water tight fit between the lower end of the casing stem and the follower so that water from the outside of the drill stem cannot leak into the interior of the casing stem at this point and a water tight fit is 115 accomplished between the shoe and the well in a manner hereinafter described.

In the showing of the drawings, we have illustrated the cutting bit 66 in the nature of an ordinary fish-tail bit, the same, from its 120 inner end being provided with a passage 67 communicating with transverse passages 68, entering from the opposite sides or faces of the bit providing outlet for the water through the drill and bit. The fish-tail or other bit 66 is secured upon the lower section 125 of the drill or bit by a coupling 69 engaging both the lower cutting member and the lower section of the bit proper, so that the lower boring member may be readily re- 130

moved from the bit and, in lieu thereof, a diamond core barrel and drill or any other means for core drilling may be attached to the bit so that a section of strata may be removed when the bit is removed from the stem, for analytical purposes.

By a construction and arrangement of parts as above described, it will be seen that both the lower boring member of the bit and the reamers, or upper cutting members of the bit, may be relieved of the heavy weight of the casing; that the weight of the bit resting upon the cutting members when boring may be varied to suit the character of rock being bored; that the bit is free from danger of injury by the casing stem by reason of the great mass of weight thereof; it being understood that the weight of the bit is sufficient at all times to cause the outward longitudinal movement of the reamers with respect to the drill stem or casing; that the bit, including the reamers and lower boring member, turns with the casing or drill stem; that the reamers produce a larger hole than that of the cross sectional diameter of the drill stem; that the reamers, arranged substantially diametrically opposite each other are effectively reinforced and locked in their operative position; that the reamers are subjected to a direct longitudinal pull when the same are brought to their inoperative position in the pockets; that the entire bit may be brought to the surface through the drill stem or casing for resharpening or replacing the cutting members, or for other purposes; that different strata may be readily removed for analytical purposes; that the construction provides for the free flow of water to both the reamers and the lower cutting member, and that a longitudinal movement of the stem 56 in an upward direction houses the reamers in the pockets and permits of the withdrawal of the entire bit for resharpening these cutting elements. The manner of withdrawing the bit will now be described.

The rod 56 has its outer end provided with a threaded boss 90 designed to receive the socket end of additional stems, or sinker bars, any desired number of which may be employed, and to the uppermost stem or sinker bar is threadedly secured the socket end of a stem 70. This stem has secured thereon a flange or collar 71 which is contacted by a spring 72 that surrounds the said stem, the opposite end of the spring contacting with a movable collar 73. The movable collar 73 is provided with outstanding radially arranged pairs of ears 74, between each pair of which are pivotally arranged, as at 75, links 76. The links 76 have their outer ends widened and bifurcated as at 77, and passing through the said bifurcated portions of the said links are pivot members 78 which secure to the said

links 76, additional links 79, the last mentioned links being pivotally connected, as at 80, to the inner or lower end of the stem 70. The pivots 78 provide journals for roller member 81, and these rollers, by the influence of the spring 72 upon the toggle arrangement provided by the links 76 and 79, are brought to engage with the inner surface of the stem or casing 15. The upper or outer end of the pin 70 is cone shaped or pointed as at 82. The frictional engagement of the rollers 81 with the inner periphery of the drill stem or casing centers the stem 56 and likewise retains the mandrel and bit in proper position with respect to the slip joint provided by the tube 20 and the sleeve 16. When the reamers are to be drawn into the pockets provided therefor, to permit the removal of the bit from the drill stem or casing, a fishing tool is employed, the same having at its lower end a slip socket 83, the bore of which, at the lower end of the said socket, being flared inwardly as at 84, and within this portion 84 of the bore are arranged clutch members 85. The outer end of the socket is preferably flared as at 86, so that the conical or pointed end 82 of the stem 70 may be properly directed into the bore of the socket. The clutch members 85 comprise two in number, being oppositely disposed, and being connected by the arms 87 to a U-shaped or hair-pin spring 88. On the top wall of the bore of the socket member is pivotally connected a catch 89 which, when engaging with the spring 85, will draw the said member upwardly in the bore of the socket, causing the clutch members to travel upon the flared walls 84 in the bore, and, therefore out of contacting engagement with the pin 70. When, however, the pointed end 82 of the pin contacts with the connecting member of the arms of the spring 88, the said spring will be brought out of engagement with the catch, the arms of the said spring bringing the clutch members 85, into engagement with the pin, and an upward movement of the member 83, through the drill stem or casing, will cause the clutch members 85 to travel over the flared or cam shaped surface 84 to force the said clutch members into tight engagement with the pin, permitting the withdrawal of the bit, including the reamers and lower boring member. The bit may be replaced by reversing the operation above described, that is, the clutch members may engage with the pin to lock the same to the socket member, and when the bit has reached its lowermost position, and the mandrel has reached its lowest point of travel, a further downward movement of the socket member 83 will cause the said socket to move over the pin which contacts with the rounded or connect- 130

ing member for the arms of the U-shaped or hair-pin spring 88, forcing the same upwardly until the spring is again engaged by the catch 89, when an upward pull upon 5 the socket 83 will release the said socket from the pin.

One of the important features of the improvement is as heretofore stated, to provide a means, whereby the drill stem will 10 provide an effective closure for the opening to be bored by the bit 66 when the cap rock of an oil deposit or oil sand has been reached. When the cap rock is partly bored by the reamers, the reamers are retracted or 15 moved into their pockets, and the entire bit, including the reamers and lower cutting member, is moved upwardly through the drill stem and removed from the well. The casing stem is permitted to gravitate by its 20 own weight or is forced against the cap rock to surround the opening made by the lower boring member of the bit, the stem resting upon the shoulders cut by the reamers, it being understood that the bit has 25 not yet reached the oil pocket.

The fishing tool is employed to withdraw the drill by actuating the mandrel, causing the reamers to be moved into their pocket, so that the entire drill is removed from the 30 casing stem. The water pumped into and through the drill stem and bit during the drilling operations to wash away the cuttings and lubricate the stem, is now bailed out and the drilling tools of an ordinary standard or cable drilling rig is inserted through 35 the rotary drill casing stem, which now serves as the casing of the well. It will be noted that the standard rig is now drilling through a dry hole, and that the weight of 40 the drill stem which is now used as a casing, is sufficient to effectively close the opening between the shoulder cut by the reamers, and the outside of the rotary casing stem, so that drainage of water from 45 up per stratum will not be permitted to enter the oil sand, when the cap rock is penetrated. We are aware that various attempts have been made to produce cutting elements in oil well drilling apparatus which include 50 reamers that are designed to be withdrawn for sharpening the same. In none of such constructions have the reamers been arranged or of a formation to permit of the direct longitudinal sliding thereof when the 55 same are brought to inoperative position, and in none of the constructions is there disclosed means whereby the drill stem will effectively close the outlet opening of the oil sand to prevent the entrance of water from 60 around the casing stem into the oil sand. Furthermore, in none of the reamer constructions which have come under our observation, can the said reamers be retracted without necessitating the elevation of the 65 stem or casing. Furthermore, in the con-

struction of no other rotary drill bit is any provision made or means provided whereby the downward pressure or weight upon the cutting members can be uniformly regulated by the driller, or whereby the said bit 70 and cutting elements are entirely free from danger of undue strains by reason of the great weight of the entire drill stem being thrown upon the bit. We also have knowledge of inventions pertaining to adjustable 75 and removable bits designed to perform the functions of reamers, that is, produce an opening greater than the cross-sectional diameter of the drill stem or casing, but, as far as we have ascertained, each and every 80 one of such devices are impracticable for the purpose devised. We believe from the foregoing description, when taken in connection with the drawings, the simplicity and advantages of our invention will be apparent 85 to those skilled in this particular art, so that a more detailed description of the construction, or advantage thereof, will not be necessitated.

We wish to call attention to the fact that 90 the tubular sleeve 16 in conjunction with the follower 20 may be used in connection with any form of rotary drilling bit now in use for the purpose of permitting the driller to relieve the bit of the weight of 95 the casing stem, and that means may easily be provided for adding weight to the bit independent of the weight of the casing stem by placing additional sinker bars inside of the casing stem and resting on the 100 top of the bit, or that an opposite result may be reached by removing sinker bars from the casing stem in order to decrease the downward pressure on the bit.

Having thus described the invention, what 105 we claim is—

1. In combination with a stem, a bit, means arranged between the bit and stem whereby the bit may be operated by the stem or detached therefrom from a point 110 above the well, an under reamer associated with said means and means independent of the stem for varying the pressure of said bit.

2. In combination with a stem, a bit connected to the stem in a manner to have axial 115 movement and means for changing the pressure of said bit.

3. In combination with a stem, a follower or shoe slidably mounted in the lower end of the stem but constructed to rotate with 120 the stem, and means relatively arranged for coöperation with said shoe and having a threaded terminal and a bit carried by said terminal.

4. In combination with a stem, a follower 125 slidable therein, means detachably connected to the follower, a bit carried by the said means, reamers slidably mounted in the said means and constructed to have a locking engagement with the follower, and 130

- means for projecting the reamers to an operative position.
5. In combination with a stem, a follower 5
slidable therein, means detachably connected
to the follower, a bit carried by the said
means, reamers slidably mounted in the said
means and constructed to have a locking
engagement with the follower and means for
mechanically moving the reamers to an op- 10
erative or inoperative position from a point
above the well.
6. In combination with a stem, a follower
slidable therein, means detachably connected
to the follower, a bit carried by the said
means, reamers slidably mounted in the said
means and constructed to have a locking
engagement with the follower, and means for
mechanically moving the reamers to an
operative or inoperative position from a 15
point above the well, said means including
the ordinary cable.
7. In combination with a stem, a follower
slidable therein, means detachably connected
to the follower, a bit carried by the said
means, reamers slidably mounted in the said
means and constructed to have a locking
engagement with the follower, and means for
mechanically moving the reamers to an
operative or inoperative position from a 20
point above the well, said means including
the ordinary cable, the connection between
the first means and follower being such that
the drill may be bodily removed from the
well by said means without disturbing the
position of the said stem.
8. In combination with a stem, a follower
slidable therein, means detachably connected
to the follower, a bit carried by the said
means, reamers, slidably mounted in the said
means and constructed to have a locking en- 25
gagement with the follower, and means hav-
ing a cam action with the reamers for mov-
ing the same toward or away from an op-
erative position.
9. In combination with a stem, a follower
slidable therein, means detachably connected
to the follower, a bit carried by the said
means, reamers slidably mounted in the said
means and constructed to have a locking en- 30
gagement with the follower, and a member
having a pin and slot connection with the
reamers for moving the same toward and
away from an operative position.
10. In combination with a stem, a fol- 35
lower slidable therein, means detachably
connected to the follower, a bit carried by
the said means, reamers slidably mounted
in the said means and constructed to have a
locking engagement with the follower and a
member having a pin and slot connection 40
with the reamers for moving the same toward
and away from an operative position, said
member having a limited slidable
connection with said means.
11. In combination with a stem, a fol- 45
lower slidable therein, means detachably
connected to the follower, a bit carried by
the said means, reamers slidably mounted in
the said means and constructed to have a
locking engagement with the follower and
means for mechanically moving the reamers 50
to an operative position from a point above
the well.
12. In combination with a stem, a fol- 55
lower slidable therein, means detachably
connected to the follower a bit carried by
the said means, reamers slidably mounted in
the said means and constructed to have a
locking engagement with the follower and
means traveling at right angle to the travel
of the reamers for projecting and locking
the reamers in an operative position.
13. In combination with a stem, a fol- 60
lower slidable therein, means detachably
connected to the follower, a bit carried by
the said means, reamers slidably mounted in
the said means and constructed to have a
locking engagement with the follower and
means for projecting the reamers to an op- 65
erative position and means traveling at
right angle to the travel of the reamers for
projecting and locking the reamers in an op-
erative position, said means being construct- 70
ed to be connected to and operated by an
ordinary cable and cable tools.
14. A rotary drill comprising in combina- 75
tion with a stem telescopic members con-
nected to said stem, supporting means car-
ried by the members, a bit, and reamers car-
ried by the said means and designed when
moved to one position to lock the bit to the
stem.
15. A rotary drill comprising in combina- 80
tion with a stem, telescopic members con-
nected with the stem, interengaging means
between said members, and a bit connected
to one of the members, a reaming device as-
sociated with said members and designed
when moved to an operative position to lock
the bit to said members.
16. A drill comprising in combination
with a stem, telescopic members carried by
the stem and having a fixed slidable connec- 85
tion with each other, supporting means car-
ried by the members, reamers slidably asso-
ciated with the said means and designed
when moving outwardly of the said means
to lock the said means to said members and a
boring member carried by the said means at
a point below said reamers.
17. A drill comprising in combination
with a stem, telescopic members at the lower
end of said stem, interengaging elements 90
between said telescopic members, longitudi-
nally-movable means having a pocket open-
ing from the sides thereof, means for
limiting said longitudinally-movable means,
reamers in said pocket, and means for im- 95

parting a longitudinal movement to said reamers to force the same outwardly of the pocket and to lock the said longitudinally-movable means to said members.

5 18. A drill comprising in combination with a stem, telescopic members at the outer end of the stem, interengaging elements between said members, means for limiting the sliding movement of the members in both 10 directions, cushion means between the members when the same are telescoped, longitudinally-movable means loosely arranged in the said members, supporting means for the said longitudinally-movable means in the 15 said members and to limit the longitudinal movement of the said means, reamers and a bit carried by the said longitudinally-movable means, and means for projecting the reamers outward of the said means and to 20 lock the bit to one of the telescopic members.

19. A drill comprising in combination with a stem, telescopic members at the end of said stem, interengaging means between 25 said members, means for limiting the movement of the members in both directions, cushion means between the members, longitudinally-movable means loosely arranged in said members, means for limiting the longitudinal movement of the longitudinally-movable means through the said members, said longitudinally-movable means having a transverse pocket, reamers in the pocket, means for imparting a longitudinal movement to the reamers to force the same outward of the pocket to lock the longitudinally-movable means to the drill stem, or for bringing the said reamers into the pocket, and a removable cutting or boring member 40 in the lower end of the bit.

20. A drill comprising in combination with a stem, telescopic members at the lower end of the stem, interengaging means between said members, means slidably arranged in said members, means for limiting the movement of the said means with respect to the said members, a collar on the outer telescopic member, said slidable means having a pocket and reamers laterally movable therethrough, interengaging means between 50 the reamers and the collar for locking the slidable means to the collar and to the stem, means for imparting such movements to the reamers, and a removable boring tool on the lower end of the slidable means.

21. A drill comprising in combination with a stem, telescopic members at the outer end of the stem, interengaging means between said members, leak preventing and 60 shock absorbing means between said members, slidable means loosely arranged in said members, means for limiting the longitudinal movement of the slidable means with respect to the said members, said slidable means having a transverse opening provid-

ing a pocket, reamers arranged in the pocket, means comprising a mandrel loosely associated with the reamers and designed, when operated, to move the reamers outward of the pocket and to bring the said reamers into 70 the pocket, and means between the said reamers and one inner telescopic member for locking the reamers to the said member.

22. A drill comprising in combination with a stem, telescopic members at the outer 75 end of the stem, interengaging means between the said members, a bit, means for limiting the longitudinal movement of the bit with respect to the said members, said bit having a transverse opening providing 80 a pocket, reamers arranged in the pocket, means comprising a mandrel loosely associated with the reamers and designed, when operated to move the reamers outward of the pocket, or to move the reamers inwardly 85 into the pocket, anti-frictional centering means for the said means and reamers arranged in the stem, means between said reamers and one of the telescopic members for locking the reamers to the said member, 90 and for connecting the first means with the drill stem, and a removable boring tool on the lower end of the bit.

23. A drill comprising, in combination with a stem, a means slidable through the 95 stem, means for limiting the sliding movement of the slidable means, said slidable means being approximately centrally provided with a transverse pocket, and said pocket having its upper and lower walls centrally 100 provided with openings, reamers in the pocket to move to the opposite sides of the openings, lugs on the inner faces of the reamers, a mandrel slidable through the openings and having its opposite sides formed with 105 straight grooves having angular lower branches designed to receive the lugs of the reamers, whereby, when the mandrel is permitted to gravitate to cause the reamers to be moved outwardly of the pocket, and when 110 the mandrel is moved in an opposite direction to bring the reamers into the pocket, operating means for the mandrel, and a removable boring tool on the outer end of the slidable means.

24. A drill comprising in combination with a stem, a shoe member having a limited slidabile movement in the stem, a collar at the lower end thereof having its inner face provided with arcuate depressions and an angular shoulder in the end of each depression, means slidable through the shoe, means for limiting sliding movement of the slidabile means, said slidabile means having a transverse pocket partly closed by the collar, 125 reamers in said pocket including body portions having their outer ends curved and their faces provided with V-shaped depressions, the cutting elements of the reamers being arranged below the depressions of 130

10 said body portions and a mandrel slidable through the slidable means and operating with the reamers to move the same outward of the pocket to bring the arcuate ends into engagement with the walls of the arcuate depressions of the collar and the depressions thereof into engagement with the shoulders of the collar when the reamers are moved in outward direction through the slidable means.

15 25. In a rotary well drill, a stem, laterally arranged longitudinally movable reamers adjacent the end of the stem, a removable boring tool below the reamers, means for projecting or retracting the reamers, and means for locking the reamers to the drill stem in their projected position and against accidental movement toward an inoperative position.

20 26. In a rotary drill, a tubular stem, telescopic members connected to said stem, a bit in said members, reamers associated with said bit and designed when moved to one position to lock the bit to the telescopic members, and a lower boring member carried by said bit.

25 27. In a rotary drill, a tubular stem, telescopic members connected with the stem, interengaging means between said members, a bit in said members, reamers associated with said bit and designed, when moved to one position, to lock the bit to the telescopic members and a lower boring member carried by the bit.

30 28. In a rotary well drill, a tubular stem, telescopic members connected to the stem, interengaging ribs and depressions between said members, a bit in said members, reamers slidably associated with the bit and designed when moved outwardly of the bit to lock the bit to the telescopic members, and a lower boring member carried by the bit.

35 29. In a rotary well drill, a tubular stem, a sleeve secured to the outer end thereof, a tube slidable in said sleeve, annular flanges on said sleeve and said tube spacing the tube and sleeve, interengaging ribs and depressions between the sleeve and tube, a bit in the tube and longitudinally movable there-through, means for limiting such movement, reamers carried by the bit and designed when moved to an outward position to lock the bit to the tube, and a lower boring member carried by the bit.

40 30. In a rotary well drill, a stem, telescopic members at one end of said stem, interengaging elements between said telescopic members, a bit longitudinally movable through the said telescopic members, means for limiting the said longitudinal movement of the said bit, said bit having a pocket opening from the opposite sides thereof, reamers in said pocket, means for imparting a longitudinal movement to said reamers to force the same outwardly of the pocket and

to lock the bit to the telescopic members, and a lower cutting member carried by said bit.

45 31. In a rotary well drill, a tubular stem, telescopic members at the outer end of the stem, interengaging elements between said members, means for limiting the sliding movement of the members in both directions, cushion means between the members when the same are telescoped, a bit loosely arranged in the said members, supporting means for the bit in the said members and to limit the longitudinal movement of the bit, reamers carried by the bit, means for projecting the reamers outward of the bit and to lock the bit to one of the telescopic members, and a removable cutting member carried on the lower end of the bit.

50 32. In a rotary well drill, a tubular stem, telescopic members at the end of said stem, interengaging means between said members, means for limiting the movement of the members in both directions, cushion means between the members, a bit loosely arranged in said members, means for limiting the longitudinal movement of the bit through the said members, said bit having a transverse pocket, reamers in the pocket, means for imparting a longitudinal movement to the reamers to force the same outward of the pocket to lock the bit to the drill stem, or for bringing the said reamers into the pocket, and a removable cutting or boring member in the lower end of the bit.

55 33. In a rotary well drill, a stem, telescopic members at the lower end of the stem, interengaging means between said members, a bit slidably arranged in said members, means for limiting the movement of the bit with respect to the said members, a collar on the inner telescopic member, said bit having a pocket partly closed by the collar, reamers arranged in the pocket and laterally movable therethrough, interengaging means between the reamers and the collar for locking the bit to the collar and to the stem, means for imparting such movement to the reamers, and a removable boring tool on the lower end of the bit.

60 34. In a rotary well drill, a tubular stem, telescopic members at the lower end of the stem, interengaging means between said members, cushion means between said members, a bit loosely arranged in said members, means for limiting the longitudinal movement of the bit with respect to the said members, said bit having a transverse opening providing a pocket, reamers arranged in the pocket, means comprising a mandrel loosely associated with the reamers and designed, when operated, to move the reamers outward of the pocket and to bring the said reamers into the pocket, means between the said reamers and the inner telescopic member for locking the reamers to the said member, and for connecting the bit with the drill

stem; and a removable boring tool on the lower end of said bit.

35. In a rotary well drill, a tubular stem, telescopic members at the lower end of the stem, interengaging means between the said members, cushion means between the said members, a bit loosely arranged in said members, means for limiting the longitudinal movement of the bit with respect to the 10 said members, said bit having a transverse opening providing a pocket, reamers arranged in the pocket, means comprising a mandrel loosely associated with the reamers and designed, when operated, to move the 15 reamers outward of the pocket, or to move the said reamers inwardly into the pocket, anti-frictional centering means for the bit and reamers arranged in the stem, means between said reamers and the inner telescopic 20 member for locking the reamers to the said member, and for connecting the bit with the drill stem, and a removable boring tool on the lower end of the bit.

36. In a rotary well drill, a tubular stem, 25 a bit carried by and slidable through the

lower end of the stem, means for limiting the sliding movement of the bit, said bit having its lower end reduced and being approximately centrally provided with a transverse pocket, and said pocket having 30 its upper and lower walls centrally provided with openings, reamers in the pocket at the opposite sides of the openings, lugs on the inner faces of the reamers, a mandrel slidable through the openings and having 35 its opposite sides formed with straight grooves having angular lower branches designed to receive the lugs of the reamers, whereby, when the mandrel is permitted to gravitate in an outward direction to cause 40 the reamers to be moved outwardly of the pocket, and when the mandrel is moved in an opposite direction to bring the reamers into the pocket, operating means for the mandrel, and a removable boring tool on the 45 lower end of the bit.

In testimony whereof we affix our signatures.

CLINTON R. BARRY.
MARSHALL L. McCLELLAND.
